UNITED STATES PATENT OFFICE.

HOWARD H. HUMMEL, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

ANNEALING BOX.

Application filed July 27, 1921. Serial No. 487,916.

To all whom it may concern:

Be it known that I, HOWARD H. HUMMEL, residing at Bethlehem, in the county of Lehigh and State of Pennsylvania, have invented certain new and useful Improvements in Annealing Boxes, of which the following is a specification.

This invention relates to annealing boxes, and in the form shown is made in a one piece metal casting. It resides in certain structural features and arrangement of parts designed primarily to prevent distortion or breakage under the strains of use due to expansion and contraction under varying temperatures. It accomplishes that result or purpose and prolongs the useful life of the box through the shape or form of the metal walls and cover of substantially uniform thickness without the necessity for additional or separate strengthening or bracing means. It furthermore avoids the necessity for a flange or thickened portion at its edges which rest on the supporting base while securing more perfectly their functions and advantages. The novel features will be more fully understood from the following description and claims, taken with the drawings.

In the drawings:

Figure 1 is a perspective view of a box embodying the invention.

Figure 2 is a central vertical longitudinal section through one end of the box but for clearness omitting a showing of the vertical corrugations in the visible side wall.

Figure 3 is a horizontal section on the line 3—3 of Figure 2 looking down.

Figure 4 is a vertical transverse section on the line 4—4 of Figures 2 and 3.

Figure 5 is a vertical transverse section on the line 5—5 of Figures 2 and 3.

Figure 6 is a section through the end on the line 6—6 of Figure 3.

Figure 7 is a similar section on the line 7—7.

Figure 8 is a vertical transverse section on the line 8—8 of Figures 2 and 3; and

Figure 9 is an outline of the shape of the bottom edge of the box which rests on the base or support.

In the preferred embodiment of the invention shown in the drawings, the anneal-

ing box is made of a single piece of cast steel or cast iron of substantially uniform thickness throughout having a top rectangular in outline and depending sides and ends having the outer surfaces of different portions comprising them at or within vertical planes passing through the marginal lines of the top, and the highest portions of the top being in a horizontal plane through the upper surfaces of the edge portions of the top. At each corner portion where the sides, ends and top meet and join each other at an angle, the body material forming the joint or connection is on a curve transversely of the line of the joint, thus avoiding sharp angles between meeting parts where breakage would be likely to occur under the strains of expansion and contraction. These curved in section corner portions may for convenience be called corrugations.

As shown in Figures 2, 4 and 5, the top of the box has a series of similar concave portions 10 extending from the curved corner side margin 11 of the box to the opposite curved side margin 12 uniformly spaced from each other throughout the length of the box. A line extending longitudinally of the box along the surfaces of these concave portions at any point will be parallel to the side margins of the top, but the curve of the concave transversely of the box is in the form of a catenary to avoid permanent distortion by expansion and contraction. It will be noted that these concave portions are much wider than the spaces between their adjacent edges, and that therefore they constitute the major portion of the top. The body material at the edges of these concave portions is curved upwardly at 13 joining the vertically extending portion 14 which at its upper portion is curved longitudinally of the box and then down to a vertical portion 15, corresponding to 14, and the lower part of the portion 15 integrally joins the next adjacent concave portion through a curved portion 16. The upper margin or surface of the top curved portion 17 of the corrugations so formed is in a horizontal plane through the upper surface of the margin of the box top, and the corrugations of course extend transversely of

the box. The concave portion at the end of the series next to the end wall of the box has its side edge connected to that end wall by the curved portion 18 (see Figure 2), a vertical portion 19 and a curved corner portion 20 integrally joining the vertical upper portion 21 of the end wall, thus forming a corrugation similar to that between concave portions. The ends of the concave portions 10 join the sides of the box through curved portions or corrugations 11 of the shape shown in Figure 1. Since the top lines of the corrugations 17 between the concave portions are in the same vertical plane as corrugations in the sides, the curved portion joining them to the sides is not so great as in the other instances mentioned, as shown at 12 in Figure 5.

The side walls of the box have corrugations 22 extending from the upper top edges 11 and 12 down to and through or including the bottom edges, and they preferably have their outer center lines in the same vertical plane transversely of the box as the outer 25 center lines of the top corrugations 17. As shown in Figure 3, they are somewhat V-shaped in section with their outer marginal lines in a vertical plane extending from the side margin of the top and with the sides 30 projecting inwardly of the box from the outer points. The outer portions where the sides meet at the point of the V are curved transversely of the corrugation and longitudinally of the box as shown in Fig. 3 to 35 avoid sharp angles. The body portions of the box between these corrugations 22 extend inwardly at an angle from the outer edge of the transversely curved or corrugated side margin 11 of the top as shown in Fig. 4, and the lower end of that angularly 40 extending part joins integrally at its lower edge a flat vertically extending part 24 parallel to the side margin of the top. The flat vertical portions 24 join the corrugations 22 at the bases of their sides 45 through slightly curved portions, as shown in Figure 3. The flat vertical portions 24 at the ends of the series are connected to similar flat vertical portions 25 of the end 50 walls by a curved portion 26 joining a flat portion 27 extending outwardly to the corner curved portion or corrugation 28 which joins the inwardly extending flat portion 29, which in turn joins the end flat portion 25 55 through the curved portion 30, as shown in Figure 3. This flat end portion 25 joins the top through the outwardly inclined portion 31, the vertical outer portion 32 and the end 60 curved portion corrugations 20 as shown in Figures 6 and 7. Each end includes two similar flat vertical portions 25 and they are connected by a corrugation 33 which is similar in shape to the side corrugations 22 and similarly arranged. As heretofore indi-

cated, the side corrugations 22, the end corrugations 33, and the corner corrugations 28, 65 extend downwardly to and including the bottom edge of the box, but they are reduced in size or contracted at their lower ends, whereby the body portion of which they are formed turns inward a short distance above the lower edge of the box, making the outward curve of that lower edge in line with the corrugation less than the outward curve above that point. This inward 70 turning of the end and side corrugations is shown at 34 and 35 in Figures 1, 3 and 5, and the inward turning of the corner corrugations is shown at 36, Figures 1 and 3. 75 This inward turning of the side, end and corner corrugations is to bring their inner and outer margins in the bottom edge in line with the inner and outer margins of additional corrugations 37 formed in the bottom edge between adjacent side, end and corner corrugations. This gives the bottom edges 80 of the sides and ends a zig zag or fluted form, shown in Figure 9, with the outer points of the curves equal distances from a center line or in spaced parallel planes. It 85 will be noted that the curves are close together longitudinally and are symmetrically arranged, thus furnishing a supporting contact surface extending laterally of the center line on opposite sides a distance as great as or even greater than that ordinarily provided in the form of a flange. This fluted form of the edge not only secures the necessary strength for supporting the box during 90 use but has the very decided advantage over a flange of permitting free expansion and contraction without permanent distortion. The curves are so numerous and the distortion is so evenly distributed that it is very 95 slight at any one point, and is not so localized as to cause permanent distortion. This is true of the series of corrugations and curved connections throughout the entire annealing box, and thus the effective useful life of the box is greatly prolonged. It 100 neither includes nor requires strengthening members or ribs.

A pair of lifting hooks or projections 38 and 39 are preferably cast integral with the body portion projecting from the flat surfaces 24 of the concave portions of the sides with their outer ends within a side plane 105 passing along the outer margins of the side corrugations 22, and therefore do not so project as to be in the way of and be struck by outside things.

From the foregoing, it will be apparent 110 that I have devised an annealing box made by a single casting. The box consists of top, side, and end walls connected by curved 115 portions at the corners. The top wall has downwardly-extending concave or catenary portions extending transversely and 120 similarly arranged.

the side and end walls are provided with vertical corrugations. The transverse concave portions and the end walls are connected together by upwardly-extending and 5 substantially parallel flat portions which are joined by curved portions. The corners between the side and end walls are provided with outwardly-extending substantially parallel flat portions which are joined by 10 curved portions. As hereinbefore pointed out the side and end walls are provided with short intervening corrugations at the bottom side in order to afford suitable footing or foundation for the box. The construction 15 of the box in this manner allows for expansion and contraction, which may be of a non-uniform character, without distorting or fracturing the box. The outwardly-extending parallel flat portions connected by 20 curved portions function to permit linear expansion of adjacent parts, or differential expansion thereof, the flat portions being capable of flexing to an extent sufficient to prevent the development of undue internal 25 stresses as might occur in a construction in which the flat portions were omitted. My improved box may, therefore, expand and contract uniformly or non-uniformly in all directions without the development of severe 30 internal stresses for the reason that the corrugated structure allows for compensation. Furthermore, the outline of the lower supporting edge may be substantially preserved, changes in linear extent of those 35 edges being compensated for by flexure of the outwardly-extending flat portions joined by the curved portions.

While one specific embodiment is shown, it will be understood that the invention is 40 not limited to that form beyond what is stated in the claims.

Having thus described my invention, what is claimed as new and desired to be secured by Letters Patent is:

45 1. An annealing box of integral cast metal rectangular in form, having a series of corrugations in its sides and ends with outer transversely curved margins extending downward from and in substantially the same vertical plane as the outer straight margins of the corrugations forming the edges of the top, the portions of the walls between adjacent corrugations extending inwardly of the box at an angle from top edge and from the outer margins of the corrugations.

50 2. An annealing box of integral cast metal rectangular in form, having a series of corrugations in its sides with outer transversely curved margins extending downward from and in substantially the same vertical plane as the outer straight margins of the corrugations forming the edges of the top, the portions of the side walls be-

tween adjacent corrugations extending inwardly of the box at an angle from top edge and from the outer margins of the corrugations and a series of transverse corrugations in its top with upper transversely curved margins in substantially the same horizontal plane as the upper straight margins of the edges of the top, the portions of the top between its edge portions and between adjacent corrugations being depressed inwardly of the box. 65 70 75

3. An annealing box of integral cast metal rectangular in form, having a series of corrugations in its sides with outer transversely curved margins extending downward from and in substantially the same vertical plane as the outer straight margins of the corrugations forming the edges of the top, the portions of the side walls between adjacent corrugations extending inwardly of the box at an angle from top edge and from the outer margins of the corrugations and a series of transverse corrugations in its top with upper transversely curved margins in substantially the same horizontal plane as the upper straight margins of the edges of the top, the portions of the top between its edge portions and between adjacent corrugations being depressed inwardly of the box on curves transversely from the side portions to the center line, their surfaces being on longitudinal lines parallel to the lines of the side margin of the box. 80 85 90 95

4. An annealing box cast as an integral piece of metal having a top rectangular in outline with spaced corrugations across it and having spaced corrugations extending therefrom down the sides and corner corrugations curved or rounded in section where the sides join each other and where they join the top, and concave portions between the corrugations, the upper margins of the corrugations where the sides join the top and of those extending across the top being in substantially a single plane. 100 105

5. An annealing box cast as an integral piece of metal having a top rectangular in outline with spaced corrugations across it and having spaced corrugations extending therefrom down the sides and corner corrugations curved or rounded in section where the sides join each other and where they join the top, and concave portions between the corrugations, the upper margins of the corrugations where the sides join the top and of those extending across the top being in substantially a single plane and the outer margins of the corrugations in each side including its corner corrugations being in substantially a single plane. 110 115 120

6. An annealing box cast as an integral piece of metal having a top rectangular in outline with spaced corrugations across it and having spaced corrugations extending

- 4
- therefrom down the sides and corner corrugations curved or rounded in section where the sides join each other and where they join the top, the outer marginal lines of said 5 corrugations being in substantially the same planes as the straight margins of the rectangular top. 7. An annealing box having sides provided with spaced corrugations extending 10 from the top to and including the bottom edges, the bottom edges being of substantially the same thickness as the balance of the sides and having intermediate corrugations between those of the sides. 15 8. An annealing box having sides provided with spaced corrugations extending 15 from the top to and including the bottom edges, the bottom edges being of substantially the same thickness as the balance of 20 the sides and having intermediate corrugations between those of the sides but extending laterally of the sides to a less extent, and the lower ends of the side corrugations at the bottom edges being contracted 25 to bring their outer margins in line with those of the intermediate corrugations. 9. An annealing box of integral cast metal 30 rectangular in form, having a series of corrugations in its sides with outer transversely curved margins extending downward from and in substantially the same vertical plane as the outer straight margins of the corrugations forming the edges of the top, the portions of the side walls between adjacent 35 corrugations extending inwardly of the box at an angle from the top edge and from the outer margins of the corrugations. 10. An annealing box of integral cast metal 40 rectangular in form, having a series of corrugations in its sides with outer transversely curved margins extending downward from and in substantially the same vertical plane as the outer straight margins of the corrugations forming the edges of the top, the portions of the side walls between adjacent 45 corrugations extending inwardly of the box at an angle from the top edge and from the outer margins of the corrugations for a predetermined distance and then in a plane 50 parallel to the top edge. 11. An annealing box of integral cast metal 55 rectangular in form having a series of corrugations in its sides with outer transversely curved margins extending downward from and in substantially the same vertical plane as the outer straight margins of the corrugations forming the edges of the top, the portions of the side walls between adjacent corrugations extending inwardly of the 60 box at an angle from the top edge and from the outer margins of the corrugations for a predetermined distance and then in a plane parallel to the top edge, the bottom edges of the sides curved or corrugated longitudinally 65 in zig zag or fluted form with the inner margin of the corrugations in said last mentioned parallel plane. 12. An annealing box having portions thereof extending on a curve in the shape of a catenary to provide for expansion without permanent distortion. 70 13. An annealing box of cast metal having portions of material width extending substantially from one edge to the opposite edge 75 in the form of a catenary. 14. An annealing box having concave sections of material width extending from a line near one margin of the box to a line near the opposite margin, the concave being 80 in the form of a catenary. 15. An annealing box having a series of concave sections of material width extending from a line near one margin of the box to a line near the opposite margin, the concave being 85 in the form of a catenary, and integral corrugations between and connecting adjacent concave sections with their outer margins in substantially the same plane as the margins of the box. 16. An annealing box of cast metal of 90 substantially uniform thickness including catenary concave portions in its top. 17. An annealing box of cast metal of 95 substantially uniform thickness including catenary concave portions in its top and corrugations between said concave portions the transverse curve lines of which are at right angles to those of the concaves. 18. An annealing box of cast metal of 100 substantially uniform thickness having a top rectangular in outline embodying a series of similar spaced concave portions extending across the top, each in the form of a catenary, and intermediate corrugations 105 across the top from one edge to the other transversely curved at their upper portions with their outer margins in substantially the plane of the top side edges and extending down in planes at substantially right angles 110 to the sides and integrally connected to said concave portion through a portion curved longitudinally of the box. 19. An annealing box of cast metal having 115 substantially uniform vertical corrugations in its sides with intermediate concave portions and integral lifting hooks on the concave portions below the top with their outer ends within the plane of the outer margins of said corrugations. 20. A cast iron annealing box having the 120 major portion of its top curved in the form of a catenary. 21. A cast iron annealing box having the major portion of its top curved in the form 125 of a catenary with intermediate relatively narrow corrugations. 22. An integral annealing box comprising top, side and end walls joined by curved

corner portions, the top wall having transversely concave depending portions connected by transverse curved portions and the side and end walls having vertical corrugations.

23. An integral annealing box comprising top, side, and end walls having curved con-

necting corner portions, the connecting corner portions between the side and end walls including outwardly-extending substantially parallel flat portions.

In testimony whereof I hereunto affix my signature.

HOWARD H. HUMMEL.
